TENSION RING CLOSURE FOR PACKING
CONTAINERS

Alfons Mauser, Cologne-Marienburg, Germany,
assignor to Mauser Maschinenbau G. m. b. H.,
Cologne-Ehrenfeld, Germany

Application June 21, 1935, Serial No. 27,805
In Germany March 28, 1935

7 Claims. (CL 220—61)

In tension ring closures two types of closure can be distinguished as regards the closure means. One type contains tension ring closures in which the tension ring has at its ends specially provided closure means, mounted usually towards the middle of the vessel, while in the other type the closure means are formed directly from the ring material and are usually found on the outer side of the ring.

10 The tension ring closure according to the invention belongs to the second category of closure types, which are mostly intended for lighter packing containers.

15 As compared with the known types of closure the construction according to the invention shows some important improvements. It is known at one end of the tension ring to press out of the material abutments in the forms of lugs, eyes or the like, which engage in corresponding recesses in the other end of the ring. The engagement 20 is mostly effected in such a manner that the ring ends when being fixed on, slide one over the other owing to the wedge action of the closure means, in order to cause the closure means to catch when the closed position of the ring is 25 reached. The engagement of the closure members is secured by means of pins, by insertion of plates, by sealing and the like. The engagement parts which are pressed out of the ring material, are found on the outer part of the tension 30 ring. On account of their large projection they are liable to damage, which not only endangers the closure but also makes it impossible to use the tension ring again, and thereby causes an unnecessary increase in the cost of the packing. 35 The projections producing the engagement are mostly placed in a flat position or transverse to the tension ring. Since however, the latter consists of thin-walled material the danger of bending over or other deformation is obvious, and 40 also implies unreliable closure. Finally, the sliding of the ring ends one over the other when the ring is fixed on, on account of the high projections, requires a considerable spreading apart 45 of the ring ends, so that a uniform pressure on the container cover and reliable sealing at the abutment of the ring is doubtful.

45 The closure construction according to the invention does not have the above drawbacks, and also has further important advantages. According to the invention the engagement parts for the closure are pressed out in the peripheral direction of the tension ring so that when made of suitable length they give a high resistance moment corresponding to the longitudinal axis

of the cross-section when engaging behind the ring which is fixed on and exclude tearing away or deformation.

The engagement parts thus pressed out at one end of the ring, slide in slots in the other end of the ring in such a manner that when the engagement positions of the projections are similarly directed, the ring ends are relatively rotated in the periphery of the thickness of the material in order to be caused to spring back 10 into their initial position when the engagement place is reached. By this means the closure position of the tension ring is secured. It is thus a kind of bayonet closure. There is no lifting of the ring ends from the edge of the container, 15 and consequently the cover packing is uniformly compressed even at the joint of the ring. Preferably two engagement parts are provided, arranged side by side in such a manner that the outer highest point of the tension ring covers 20 any projections. Since the latter need only project with the ordinary thickness of material and are covered by the overlapping ring end, the tension ring in practice has no projection at the joint. Damage to the closure part by rolling the 25 container on the tension ring or by turning it over is therefore excluded.

Instead of similarly directed engagement parts it is also possible to provide oppositely directed abutments. In this case the rotation of the 30 ring ends is avoided and the parts formed by the slots in the ring ends when the ring is applied are forced back resiliently by the thickness of the engagement members, in order that when the closed position is reached the projections may 35 be caused to engage one behind the other.

The securing of the closure against undesired loosening is effected according to the invention by the provision of securing plates, pins or seals and by suitable construction of the engagement 40 members.

In a modified form of the device according to the invention the tension ring ends having engaging lugs are each provided in order to secure the closure, with fastening plates, the ends 45 of which are provided with elongated openings. In the closed position these openings lie side by side in a known manner, so that a securing pin can be placed through them, the projecting end of which has a hole for taking the seal 50 cord. After the securing pin has been inserted it is not possible to separate the overlapping ring ends from the edge of the container, or to release the tension ring from the closed position. The closure formed in this way in combining 55

various known features provides an entirely reliable closure arrangement for packing containers with completely removable cover, which also has the advantage over the known devices of greater cheapness. Even when the lugs are deformed the closure is still reliable because the lugs cannot be flattened as the thickness of material is sufficient to ensure engagement in any case. The closure parts are protected by the edge of the cover and lie towards the middle of the container. They are scarcely subjected to any strain and can therefore be made of very thin material.

A number of constructional examples of the invention are illustrated in the accompanying drawings.

Fig. I shows the tension ring before the closure members have engaged, and Fig. II shows the same after engagement. Fig. III shows a cross-section of the tension ring closure and Fig. IV a plan.

1 is the tension ring, 2 the container cover, 3 the container wall, 4 the cover packing and 5 the depressions which may be provided at the ends of the ring for a tensioning tool. According to Figs. I to IV two projections 6 are pressed out of one end of the ring, which, when the ring is applied, slide in the slots 7 against the oblique parts 8, in order to catch in the opening 9. In the construction according to Figs. I to IV the closure is fastened by means of plates 10 secured on both ends of the ring at the inside or the outside, which plates are provided in a known manner with bushes 11 which in the closed position lie side by side and receive a securing pin 12, which can be secured by sealing. This fastening only has the object of preventing the overlapping ring end being disengaged. The plates 10 are subjected to little strain and can be made of comparatively thin material.

Fig. V shows a front elevation and Fig. VI a cross-section of the tension ring 1 with oppositely arranged engagement members 6a, 9. The end carrying the recesses 9 is forked and has the two oblique parts 8a, on which the projections 6a of the other end slide. In order to reduce the resilience to the halves of the thickness of the material of the ring, the end carrying the projections 6a may be provided with a slot 13 so as to form two parts 14, each having a projection 6a. In this case the closure is fastened by constructing the projections 6a as clips (Fig. VI). By this means the overlapping ring end is prevented from being forced off and released. This type of closure has the particular advantage that no additional means are required for fastening the closure. For receiving the sealing wire the ring ends may be provided with coinciding holes 15. Instead of the clip-like construction of the projections 6a, further engagement members may be provided on the edges of the tension ring for fastening the closure, as is illustrated in Fig. VII showing an elevation of the tension ring from within and Fig. VIII showing a plan view. The outer part 16 has a projection 17 pressed out which engages in a corresponding recess 18 on the other end of the ring. When the ring is fixed on the oblique projection 17 slides over the lower ring end and on account of the resilient spreading of the part 16, catches in the recess 18 at the moment when the projections 6 engage. The engagement of the projection 17 se-

cures the overlapping ring end sufficiently against being forced off and released. The part of the ring ends which carries the engagement parts 17, 18 may be bulged outwards somewhat to provide a deeper engagement of the projection 17 and better provision of holes 18 for the seal wire.

A further constructional form of the tension ring closure according to the invention is illustrated in Fig. IX in elevation, in Fig. X in plan 10 and in Fig. XI in a lateral cross-section. At the upper and lower edge of one ring end are provided the pressed out projections 20 which on account of their oblique construction, force the other overlapping ring end apart resiliently 15 when the ring 1 is being fixed on, in order to catch in the recesses 21 when the closed position is reached. In this case the ring ends are not forced away from the edge of the container. For preventing the overlapping ring end and the closure from being forced off, use is made of a thin sheet metal strip 22 fixed in the lower ring end, which completely surrounds the ring. The overlapping ring end has two oppositely directed pressed out clips 23 through which the strip 22 is drawn. The latter has at the upper end a slot 24 level with the edge of the ring, through which the other end 25 is placed before being bent downwardly. Immediately behind the slot is a hole 26 for receiving a seal wire 27 which prevents the tongue 25 being pulled out of the slot 24.

A further constructional example of the invention is illustrated in Fig. XII showing an elevation of the tension ring, and Fig. XIII showing a plan view of the closure. The one end of the tension ring a has a lug c pressed out of the material, which engages in the recess d of the other end of the ring. When the ring is fixed on, for example by means of a tool engaging in the holes e, the edge e of the overlapping ring slides on the oblique lug surface c and produces a spreading so that when the closed position is reached the lug catches in the recess. At the same time the bushes f of the plates f secured to the ring ends lie side by side so that the securing pin g can be pushed through. The projecting end of the securing pin has the boring h for receiving a sealing cord. It is obviously within the scope of the invention to use instead of the lug described here, another engagement member pressed out of or provided on the ring material.

In accordance with the invention in all the engagement projections of various constructional forms the pressing is effected in such a manner that the strain due to the ring tension is directed towards the raised web of the projections.

What I claim is:—

1. A tension ring closure for packing containers, comprising a ring having at one end a plurality of webs extending longitudinally and pressed out of the material of the ring to project radially and at the other end oblique parts on which the projections can slide so as to be deflected tangentially but not radially and behind which the projections catch in the closed position of the ring.

2. A tension ring closure as claimed in claim 1 in which the recesses for the engagement of the projections are similarly directed.

3. A tension ring closure as claimed in claim 1, and having plates secured to the ends of the ring towards the middle of the container, each plate having a longitudinal bush, the bushes lying side 75

by side in the closed position of the tension ring so that a securing pin can be inserted, having at its projecting end a hole for receiving a sealing cord.

5. 4. A tension ring closure as claimed in claim 1, in which the height of the projections is approximately equal to the thickness of the material of the ring.

5. A tension ring closure as claimed in claim 1, 10 in which the recesses for the engagement of the projections are oppositely directed and the end of the ring carrying the projections has a longitudinal slot.

6. A tension ring closure as claimed in claim 1, 15 in which the outer edges of the overlapping ring

end are provided with oblique projections adapted to slide against the other ring end when the ring is being applied, and to engage in corresponding recesses on the other ring end when the closed position is reached, for the purpose of fastening the closure.

5

7. A tension ring closure as claimed in claim 1, having a sheet metal strip secured in the hollow of the cover ring end and completely surrounding the overlapping ring end, and a clip arranged on the overlapping ring end, the strip having a slot 10 at one end through which its other end is passed before being bent over and secured by sealing for the purpose of fastening the closure.

10
